UNITED STATES PATENT OFFICE.

PATRICK FOGARTY, OF OXFORD, OHIO, ASSIGNOR OF ONE-HALF TO OWEN MCCOY, OF SAME PLACE.

FOLDING COOP.

SPECIFICATION forming part of Letters Patent No. 410,511, dated September 3, 1889.

Application filed May 13, 1889. Serial No. 310,522. (No model.)

To all whom it may concern:

Be it known that I, PATRICK FOGARTY, of Oxford, in the county of Butler and State of Ohio, have invented certain new and useful 5 Improvements in Folding Coops; and I do hereby declare the following to be a full, clear, and exact description of the invention, such as will enable others skilled in the art to which it pertains to make and use it, reference being 10 had to the accompanying drawings, which form part of this specification.

My invention relates to an improvement in metallic folding coops; and it consists in the combination of four metallic end pieces which 15 are pivoted together, and to which the back of the coop is rigidly secured, the front grated portion, the hinged end pieces, and a metallic plate which is placed over the grated portion at night so as to protect the fowls, as will be 20 more fully described hereinafter.

The object of my invention is to produce a metallic folding coop which can be closed up at night in such a manner that no access can be had to the fowls in the coop, and which, 25 when not in use, is adapted to be folded up and packed away.

Figure 1 is a vertical section of the coop extended for use. Fig. 2 is a similar view showing the parts folded up.

30 A represents the metallic end pieces, which are hinged together at their upper ends and to which the solid metallic iron back B is rigidly secured in any suitable manner. The upper end I of the back B is curved upward 35 and bent down over the top of the coop, as shown, so as to allow free ventilation to the fowls at night, when the coop is closed by the front plate. To the front end pieces A are hinged or pivoted in any suitable manner the 40 triangular end pieces C, which are provided with slots through which any suitable fastening devices attached to the rear end pieces A are passed. The front end pieces are connected together by the iron rods or slats D, 45 which form the front of the coop.

At night, when the front of the coop is to be closed, a solid metallic plate G, provided with

hooks H on its under side, so as to catch over the rods or slats, is placed over the front of the coop, as shown. During the day this 50 plate is not used, and the front of the coop is left open, so that the small fowls can pass freely in or out. At night, when the fowls are to be protected from animals which prey upon them, this plate is placed in position over the 55 front of the coop, as shown. The coop is then closed at all sides, while ample breathing room is left at the top under the ends of the turned-over portion I of the back B.

When the coop is no longer needed, the end 60 pieces are folded inward inside of the front of the coop, and then the back is closed down upon them, thus folding the coop into a very small space.

This coop being made entirely of iron, no 65 animals can gnaw their way through so as to get at the fowls, and hence they are absolutely safe at night.

Having thus described my invention, I 70 claim—

1. In a folding coop, the combination of the hinged end pieces, the back secured thereto having its upper end curved over the top of the coop and left open at the ends for ventilation, with the triangular end pieces, and the 75 rods or slats connecting the front end pieces and forming the front of the coop, substantially as described.

2. In a folding coop, the combination of the end pieces hinged together at their upper 80 ends, the back secured thereto having its upper end curved over the top of the coop and left open at the ends, the triangular end pieces, the rods or slats connecting the front end pieces, and the removable metallic plate 85 provided with hooks for catching over the rods, and which closes the front of the coop at night, substantially as described.

In testimony whereof I affix my signature in presence of two witnesses.

PATRICK FOGARTY.
